NEW YORK.

FOOTBALL GAME.

Application filed March 19, 1926. Serial No. 95,840.

This invention relates to improvements in games to be played in the home and more particularly to a football game and the principal object is the provision of a game which is similar to the actual game of football as played on the field and which enables the players of the game to carry out the moves of the football players or men in substantially the same fashion and method as in the outdoor football game, and in which strategy and skill form a decided factor in the success or non-success of the players.

To the accomplishment of the foregoing and such other objects as hereinafter appear, this invention consists in the construction, combination and arrangement of parts hereinafter described and then sought to be defined in the appended claims, reference being had to the accompanying drawings forming a part hereof and which show merely for the purpose of illustrative disclosure a preferred embodiment of our invention, it being expressly understood, however, that various changes may be made in practice within the scope of the claims without digressing from our inventive idea.

Another object of this invention is the provision in combination in a game of this character of game pieces or men which simulate in appearance and posture the human football players or men, certain of the pieces or men being formed so as to stand in a standing running position to receive and carry the ball and others in a kneeling charging position, whereby in playing the game the kick off, runs, scrimmages, forward passes, interference, taking out and other plays are all duplicated in a very lifelike manner and fashion.

In the drawings—

Figure 1 is a perspective view of a game board or cloth and other paraphernalia of the game with the game pieces or men arranged in a scrimmage formation as in playing the game.

Figure 2 is a perspective view of two game pieces or men, one being one of the backs or ends carrying the ball and the other being one of the linemen tackling the ball carrier.

Figure 3 is a perspective view of two of the game pieces or men, both of these being line-

men shown in the position which results from taking out interference and the like.

Figure 4 is a perspective view of a miniature football and tee used in the game.

The game may be played on a game board or on a cloth or similar medium and the field is laid out on a scale to correspond to the outdoor game of football. The field is marked with the boundary lines 1 and 2 and the five-yard lines 3 extending transversely of the field. In addition to that the small squares 4 are provided by additional longitudinal and transverse lines on substantially any scale that may be desired. At the end of each field are placed goal posts. These may be of various forms. We have found the form illustrated to be a good one for the practice of this game. The goal posts 5 have bases 6 and cross standards with the net 7, which is adapted to receive the ball and prevent the same being lost. The ball itself 8 is a miniature football of any suitable material, being of such size as to accomplish the functions hereinafter set forth. In kicking off or kicking a goal a small tee or elevation 9 is provided to receive the ball 8 and the kicking operation is performed by the player flipping his finger against the ball, causing it to fly through the air as in the outdoor game.

A very important feature of this invention resides in the game pieces or men or players who are used for the purpose of playing the game. These game pieces or men are illustrated in Figures 2 and 3, and, as shown, are preferably in two forms, one form 10 representing the linemen, and the other form 11 representing the backs and ends. The former game pieces or men are shown in a kneeling charging position, being supported upon one knee or foot and on one hand, just as the posture simulating the position of the players in the actual game. The other game pieces or men 11 are shown in a standing running position, as well as a ball receiving and carrying position. An important feature about these last-mentioned game pieces or men is the position of the arms 12 which are extended and turned and bent so as to catch and receive and hold the ball 8. These arms are so shaped and proportioned and arranged

- and the ball 8 is of such a size that it will rest between and within the arms of these game pieces or men 11. Of course, the ball 8 is passed and placed in the arms of one of 5 the game pieces or men 11 by the human player of the game, but the placing of the ball in the arms of these game pieces or men affords the opportunity for fumbles just as in the outdoor game of football. All of 10 the game pieces or men 10 and 11 are or may be decorated to imitate uniforms or colors of schools, colleges or clubs and carry numbers on their backs and have head guards or other playing paraphernalia, and in fact 15 duplicate to a marked degree the appearance of the players on the field of the outdoor game of football. Of course, these game pieces or men are decorated so that two teams may be represented as opponents.
- 20 The game is played in accordance with the same rules as the outdoor game of football and all the various plays of that game may be carried out by means of this invention. On the kick off and from scrimmage 25 the game pieces or men are arranged by the human player having charge of each side in just the same fashion as the players in the outdoor game of football. The ball is put into play the same way and interference 30 is formed in the same way and defending players are taken out and the interfering players taken out and the ball carried in the same way. As a matter of fact in 35 actually playing the game the use of the game pieces or men to take out the defense or take out the interference results in a most accurate duplication of many of the scenes on the football field.
- 40 Of course, the carrying out of the game is to be in accordance with a certain system of moving and this is the only substantial difference between this game and the outdoor football game, but that very factor is an advantage in playing this game in 45 that all element of chance, such as spinning counters or throwing dice, is eliminated, and the result of the game depends upon the skill and strategy of the human player in charge of each side. This, of course, adds 50 to the interest of the game, making it available to players of all ages, young or old. Furthermore it takes it out of the game class alone and puts it into the class of devices for instructing or coaching as it serves admirably for not only illustrating the plays that actually occur or should occur in actual 55 football games but also enables the players to practice the various offensive plays and the defenses for these various plays, and also to practice strategy and the defense for the strategy that might arise in actual football games. It, therefore, affords an excellent instructive medium for use by all persons actually engaged in playing football or 60 the instruction and coaching of players 65

therein, as well as an indoor game of attractive appearance and engrossing interest.

As stated above, various procedures may be provided for playing this game and determining the method of play and one procedure will now be described. The game pieces or men are lined up for the kick off as in the outdoor game. The ball is kicked by the player of the side having 70 possession of the ball by flipping the finger, as previously described. If the ball rests on a square occupied by one of the receiving game pieces or men, it is then placed in his arms by the player having charge of 75 that side with the opportunity for a fumble, above referred to. The player of the receiving side then moves each of his game pieces or men in accordance with a predetermined procedure or method. In the field 80 illustrated in accordance with the plan being described, each game piece or man may be moved through one complete square either sidewise, forward, backward or diagonally, and also may be moved forward or sidewise 85 two spaces and one space at right angles thereto, corresponding to the movement of the knight in chess. Each game piece or man of the receiving or offensive side or team is moved by the player having charge 90 of that side in accordance with this method or procedure, the effort, object and intent being to advance the ball, form interference 95 for the game piece or man with the ball and take out the defensive game pieces or men. Then the player having charge of the opposing or defensive side or team moves each game piece or man on his side 100 in accordance with the same method or procedure, the effort, object and intent being to prevent or stop the advance of the ball, take out the interfering game pieces or men, tackle the game piece or man with the ball and in general to organize the defense 105 to meet the offensive play to prevent gain. 110 When two game pieces or men occupy the same space they are taken out either of the interference or of the defense as the case may be. Moves are made by the players in charge of the opposing sides or teams in alternation until the game piece or man carrying or running with the ball is downed by one of the game pieces or men of the opposing team or side occupying the same square, 115 or until the game piece or man with the ball has cleared the field and makes a touchdown. When the ball is downed the game pieces or men are lined up for scrimmage 120 in the same manner and fashion as the players in the ordinary outdoor game, and the above method or procedure followed. Forward passes, fumbles, goal kicks, punts, may be made, and in fact every play of the outdoor game of football may be duplicated in 125 130

The game pieces or men may be formed, molded or cast in any suitable way and of any suitable material. It is to be noted that the linemen are rather nicely balanced 5 on one hand and one foot in charging position, which results in very realistic tumbling of these men when they have bodily contact with each other. This is a material factor in adding to the lifelike character 10 of the game and the attractive appearance thereof.

What we claim is:—

1. In combination in a game of the character described adapted to reproduce the appearance and the plays of the outdoor game of football on a game board, a plurality of game pieces or men formed to simulate the appearance of human football players on a small scale, certain of said game pieces or 15 men being formed so as to rest on one hand and part of one leg in a so-called charging position to simulate the appearance of the linemen of a football team composed of human players.
2. In combination in a game of the character described adapted to reproduce the appearance and the plays of the outdoor game of football on a game board, a plurality of game pieces or men formed to simulate the 20 appearance of human football players on a small scale, certain of said game pieces or men being formed in a standing, running and ball receiving position with arms extended and bent to receive a ball, said game 25 pieces or men constituting the ends and backs of the team.
3. In combination in a game of the character described adapted to reproduce the appearance and the plays of the outdoor game of football on a game board, a plurality of game pieces or men formed to simulate the appearance of human football players on a small scale, certain of said game pieces or men being formed so as to rest on one hand and part of one leg in a so-called charging 30 position to simulate the appearance of the linemen of a football team composed of human players, and certain others of said game pieces or men being formed in a stand- 35 ing running and ball receiving position with 40

arms extended and bent to receive a ball, said game pieces or men constituting the ends and backs of the team.

4. An indoor football game adapted to be played on a game board or the like including a field outlined on the game board with marginal lines and having a plurality of longitudinal and transverse lines to form squares or rectangles on said field, goal posts at each end of the field, a miniature football, a tee on which the football may be supported for simulating a kick in football, a plurality of game pieces or men, said game pieces or men being sufficient in number to form two sides or teams and being made 55 and decorated in the form of human football players, certain of said game pieces or men being formed so as to rest on one hand and part of the opposite leg to simulate a charging position, said game pieces or men being 60 the linemen, and certain others of said game pieces or men being formed in a standing running and ball receiving position having their arms extended and bent so as to receive said ball when placed therein, said 65 last-mentioned game pieces or men being the backs of the team, whereby the appearance and the plays of the outdoor game of football may be simulated and carried out on said game board. 70

5. In combination in a game of the character described adapted to reproduce the appearance and the plays of the outdoor game of football on a game board, a plurality of game pieces or men formed to simulate the 80 appearance of human football players on a small scale, certain of said game pieces or men being formed so as to rest on one hand and part of one leg in a so-called charging position to simulate the appearance of the 85 linemen of a football team composed of human players, said game pieces or men being balanced on said supporting parts so as to be readily upset or tumbled upon contact with another game piece or man. 90

In testimony that we claim the foregoing we have hereunto set our hands this 11th day of March, 1926.
